UNITED STATES PATENT OFFICE.

HARRY S. MYERS, OF VAN, PENNSYLVANIA.

ARRANGEMENT OF WINCH ELEMENTS.

1,413,287.

Specification of Letters Patent. Patented Apr. 18, 1922.

Application filed February 3, 1922. Serial No. 523,956.

To all whom it may concern:

Be it known that I, HARRY S. MYERS, a citizen of the United States, residing at Van, in the county of Venango and State of Pennsylvania, have invented certain new and useful Improvements in the Arrangement of Winch Elements, of which the following is a specification.

This invention relates to an arrangement 10 of winch elements, and more particularly to the disposition of the elements of a hoist machine in which it is desired to secure a maximum effective winding drum capacity to a given width of space available for the 15 winch as a whole. The particular adaptation selected for the purpose of illustration is a hoist attachment for a tractor, in which the available space is that defined at the rear of the machine by the tractive wheels. The 20 winding drum in such an attachment must have sufficient width to accommodate the necessary length of wound cable without interfering with the coupling and operation of a tractor drag bar, particular reference 25 being had to the Fordson tractor. Such an attachment comprises a framework upon which is supported the active elements of the winch, and this framework is attached to the differential housing of the tractor and 30 to the drag bar casing. However, it will be understood that the invention may be employed in any situation in which economy of space is a fundamental requirement.

The object of the invention is the production 35 of a hoist attachment which will occupy a minimum of space and have a maximum of winding capacity. A further object is the arrangement of hoist elements upon a supporting framework in such a manner that a minimum width of framework can be used 40 with a winding drum of large capacity.

A further object of the invention is the disposition of elements in a hoisting machine, which will distribute the driving 45 strain upon the parts best capable of sustaining them. A further object is the associating of hoist elements in connection with elements of a tractor in such a manner as to obviate the necessity of the provision of a 50 clutch as an element of the winch, and the consequent saving of space occupied by such clutch.

A further object of the invention is the 55 associating with a drum-carried drive gear of a drive pinion meshing therewith and shiftable to ungearing position within the

contour of the drum, whereby an economy of space for the winch as a whole is secured. A further object is the provision in connection with a pinion shifting in this manner of 60 a guard to prevent the winding of cable upon the drum to such an extent as to make it impossible to shift the pinion. A further object is the partitioning of the drum whereby a full winding of cable may be secured 65 through a portion of the drum and a narrower winding throughout the remainder, enabling the tractor to be used for towing or hauling by the attachment of a draw bar.

Other objects and advantages of the invention will hereinafter appear in the following description and the novel features thereof will be particularly pointed out in the appended claims.

Like reference characters indicate like 75 parts throughout the several figures of the drawings, in which—

Figure 1 is an elevation of the winch of my invention showing it applied to the rear of a tractor.

Figure 2 is a section taken upon the line 2—2 of Figure 1 showing the position of the guard for the drive pinion,

Figure 3 is a similar view showing a modified form of said guard.

Figure 4 is a plan view of the parts shown in Figure 3,

Figure 5 is a detail sectional view of the mounting of the drive sprocket, and

Fig. 6 is a side elevation of a tractor with 90 one of the wheels removed and my attachment carried thereby, and Fig. 7 is a perspective view of the frame element of my hoist attachment as it would appear with the operating elements of the winch removed 95 therefrom.

It will be understood that the invention may be varied in its details of construction and that the specific embodiment illustrated and described herein is only indicative 100 thereof; the said specific embodiment, however, is one which has been found to be practical in its construction and operation.

The winch is supported in any suitable framework 10, there being provided bearings 11, 12 and 13 thereon for a driven shaft, a drive shaft and a shift rod, respectively, which are mounted in substantial parallelism. The driven shaft carries the winding drum 14, the drive shaft carries the drive 110 sprocket 15 and the drive pinion 16, while the shift rod carries the yoke 17 and is ac-

tuated by the lever 18. The numerals 19, 20 and 21 have been chosen to designate, respectively, the driven shaft, drive shaft and shift rod.

5 These and other parts of the hoist will now be specifically described and their individual functions pointed out, after which a recital of their conjoint operation will be given.

10 The hoist is shown as embodied in an attachment for a tractor but its use is not so limited; there is one result obtained in the tractor to which special attention may be called. Between the rear or tractive wheels 15 22, 22, of a motor vehicle of the Fordson type is the differential housing, below which is a draw bar casing to which the lower member 24 of the frame 10 is secured. When the tractor is used for hauling another implement, a drag bar is attached to the eye plate 25. It will be appreciated therefore that in order to provide a facility 20 of attachment of this drag bar, it is necessary that the cable wound upon the drum 14 25 shall not exceed a certain thickness of wind and hence the desirability of providing a winch having a maximum of drum width in a given width of available space for the hoist machinery as a whole. This result 30 cannot be accomplished through the provision of a smaller sized drum, since it is desired to take advantage of the larger sized drum at times when the tractor is not being used for hauling purposes, as hereinafter 35 will appear.

In my copending application for patent serially numbered 532,992 filed January 31, 1922, I have shown, described and claimed the particular construction of winding drum

40 and mounting therefor whereby a maximum of width of drum is obtained between the sides of the framework 10. Briefly, this drum is keyed to the shaft 11 at both of its ends, and at one end carries as a part there- 45 of the gear 26 protected by a suitable guard 27. At the opposite end of the drum is the brake 28 cooperating with the band 29 and operating lever 30 to stop or retard the driving of the hoist when desired.

50 As shown in Figure 1, I have provided the drum with a removable partition 31, such as is common in the art of winches, providing two drum portions, the smaller of which is shown to the left of the figure. The cable 55 is attached at one end to the drum in any suitable manner. If it is desired to wind the cable upon the drum preparatory to transporting the tractor to another place or for use in hauling other implements, it is 60 permitted to wind upon the smaller portion of the drum until that portion has been completely filled. It is then passed through a slot in the partition 31 and permitted to wind upon the larger portion until the re- 65 mainder of the cable has been wound. It

will be seen however that by winding the cable upon the smaller portion to the limit of that portion's capacity, the number of layers of cable upon the larger portion will be greatly decreased. The space saved is 70 sufficient to permit of the easy coupling and operation of a draw bar in connection with the eye plate 25.

The full capacity of the drum is desirable in its use as a hoist attachment for a tractor 75 in the oil fields. Its two major uses here are to bail a well and to draw a casing from the well. To bail wells requires a long length of cable, and it is necessary to carry, say, twenty-five hundred feet of three-eighth 80 inch cable for this purpose. In drawing a casing from a well, a cable of larger size but not so long is required. In either event a drum of large capacity is desirable. In use it is usual to wind upon the smaller 85 portion of the drum the excess of cable over that necessary to the particular use, which leaves the larger portion of the drum for actual operating purposes.

The drum is driven in the hoisting operations by means of the pinion 16 slidably keyed to the shaft 20; and when in mesh with the gear 26, the pinion lies with its face in substantial contact with the extension 32 of the bearing 12. If now the cable 90 were wound upon the smaller portion of the drum to its utmost capacity, the pinion 16 could not be slid out of mesh to its inactive position shown in Figure 1. I have therefore provided a guard 33 lying under the 95 pinion when in its inactive position and preventing the winding of the cable upon that portion of the drum in excess of a certain amount.

The guard is shown in Figure 2 and comprises an attaching end secured to a portion of the framework. It extends sufficiently forward to lie fully under the pinion and is curved upward slightly at its forward end. Being made of stiff material and bolted at the point 35 to the rail of the frame, it is sufficient for the purposes intended. But in Figures 3 and 4 I have shown a modification in which the guard 33 is provided with an attaching leg 34 braced at 35 by the angle 10 and the forward end has been extended and bent to lie in a plane with a portion of the gear guard 27, and a connector 36 is provided for securing this end to said guard. Through this connector 40 these two parts will mutually brace each other, and insure that the forward end of the guard will not engage the teeth of either the gear 26 or the pinion 16. It will be appreciated that the guard 33 will act as a 45 guide to the operative of the hoist in determining the winding capacity of the smaller portion of the drum, and that it will form a brake for the overwinding of the cable 50 upon this portion of the drum. A suitable 55

connector 36' of peculiar shape extends from the bearing 12 to the gear guard 27, as shown in Figure 1.

It will be obvious that the provision of 5 the sliding pinion obviates the necessity of a clutch, and its mounting so as to shift into an inactive position within the contour of the drum does not increase the width necessary for the hoist as a whole. This 10 results in a distinct saving of space due to the absence of a clutch. It also reduces the number of elements in a hoist transmission, as the pinion was necessary even though a clutch were present.

15 In my copending application for patent serially numbered 532,991 filed January 31, 1922, I have described and claimed the pinion mounting and shifting mechanism shown herein. Briefly set forth, this comprises a 20 slideable mounting of the pinion upon the shaft 20 and providing it with a grooved collar 37 engaged by the yoke 17 secured to the shift rod 21. Upon a shifting of the rod 21 the pinion will be moved into 25 and out of operative relation with the gear 26. The rod 21 is mounted in ears rising from the bearings 12, 12, and to limit the movement of the rod in one direction a pin 38 is passed through an aperture in the rod 30 and comes into contact with the face of one of the ears, as clearly shown in Figure 1. The limit of movement of the shift rod in the opposite direction is controlled by the pinion face coming into contact with the 35 end of the extension 32 of bearing 12 as heretofore explained. To shift the rod a lever is provided having one end attached to the framework and pivotally connected intermediate its ends to the shift rod by a 40 special connection 39. All of these parts are described more in detail in my said co-pending application.

Beneath the guard 40 is a driving sprocket held to the shaft 20 and by means of which 45 power is received from the engine of the tractor through the medium of a sprocket chain and pinion on the pulley shaft. The particular mounting of the sprocket on the shaft 20 is clearly shown in Figure 5. The shaft 20 carries a collar 47 which is held by a set screw against one face of the bearing 12. On the shaft at the other side of the bearing is mounted the hub 48, held by a set screw, the hub being provided with a flange 49 to which 55 is bolted the sprocket 15. It will be seen that the collar 47 and hub 48 abutting opposite sides of the bearing 12 and held to the shaft 20 constitutes means for maintaining the shaft against lateral movement in the frame.

60 From the bearing 12 to the right of Figure 1 there rise two lugs 41, in which is mounted a short shaft 42 having keyed thereto at one end the cam 43, which is encircled by the brake band 29. It will be apparent that the 65 movement of the lever 30 in proper direction

will cause the brake band to grip its drum in a manner to stop or retard the movement of the winding drum in unwinding under the weight of a load.

There is an extension control 45 for the 70 clutch of the motor vehicle, this being shown in the form of a lever with the pivot or bearing in the connector 46 from the frame 10, which supports at its outer end the guard 40.

In Fig. 7 I have shown the frame work of 75 my winch with the operating elements removed, said frame work comprising two transverse rails 24 and 24' to which are secured the two attaching angles 50, 50. Connecting the ends of the transverse rails are 80 bearing-carrying members 52, 52 which have a generally arched formation. These bearing-supporting members comprise horizontally disposed portions 53 and slanting portions 54 connected by the vertically disposed 85 members 55, which last named portions are located at a distance from the transverse rails and constitute the highest portion of the arched members. On these vertically disposed portions are located the bearing members for the drum shaft, affording maximum space between the rails 24, 24' and the frame sides 52 for the drum 14 and its associated elements. On the horizontally disposed portions 53 are located the bearings for the drive 90 shaft and shift rod. The frame may be 95 suitably braced as shown at 56 and 57.

In my co-pending application for patent, Serial No. 518,980, filed November 30, 1921, I have described and claimed the hoist at 100 attachment in combination with the tractor and its driving mechanism.

From the foregoing description the operation of the device should be clear. Power from the engine is received by the right end 105 of the shaft 20, and when the pinion is in mesh with the gear 26, the drum is driven by reason of the key connections of its ends with the shaft 19. It will be seen that available 110 space for the hoist in the present embodiment may be indicated by the distance between the wheels of the tractor. It will be appreciated that the parts of the winch as herein shown are arranged in such a manner to secure a maximum winding capacity for 115 the drum and that the larger portion of the drum is centered in this space.

Having described my invention, what I claim as new and desire to secure by Letters Patent is:

1. In a hoist, a drum having a gear at one end, a drive pinion meshing with said gear, means for shifting the said pinion out of mesh with said gear and into the contour of said drum, and means for preventing the 125 winding of cable upon said drum into the path of said pinion.

2. In a hoist, a frame, a drum mounted in said frame and having a gear at one end, a drive pinion mounted upon said frame and 130

meshing with said gear, means for shifting said pinion out of mesh with said gear and into the contour of said drum, and a guard projecting from the frame between said drum and pinion to prevent the winding upon the drum of cable in quantity sufficient to prevent the shifting of the pinion.

3. In a hoist, a drum with a gear at one end and a partition dividing the same into 10 two winding portions, a pinion meshing with said gear, means for shifting said pinion out of mesh with the gear and into the contour of said drum portions, and a guard separating the pinion from one portion of 15 the drum to prevent overwinding of cable upon that portion of the drum into the path of said pinion.

4. In a hoist, a frame having spaced members carrying bearings, ears upon certain of 20 said bearings, a drum shaft and a drive shaft mounted in said bearings, a shift rod mounted in said ears, a drum and associated gear and brake track on said drum shaft, a pinion and a drive sprocket upon said drive 25 shaft, a yoke and lever upon said shift rod, said shift rod, yoke and lever constituting means for shifting said pinion out of mesh with said gear and into the contour of said drum, all of said parts lying within 30 the contour of said frame members except said drive sprocket.

5. In a hoist attachment, the combination of a frame comprising transverse rails, arched bearing-carrying members connecting 35 said rails, a shaft and drum mounted in bearings upon said arched members at their point of maximum height, a drive shaft

mounted in bearings near one of said transverse rails, a pinion on said drive shaft and an intermeshing gear on said drum located at 40 one side of said attachment, a brake track and band carried by said drum and brake operating mechanism carried by one of said arch members at the opposite side of said attachment, and means for shifting said pinion out of mesh with said gear comprising a 45 lever in proximity to said brake operating mechanism.

6. In a hoist attachment, the combination of a frame comprising transverse rails, bearing-carrying members connecting the ends of said rails and comprising horizontally and vertically positioned portions, a shaft and drum mounted in bearings upon said vertical portions, a drive shaft mounted in bearings upon said horizontal portions, a pinion on said drive shaft and an intermeshing gear on said drum located at one side of said attachment, a brake track and band carried by 50 said drum and brake operating mechanism carried by one of said horizontal frame portions at the opposite side of said attachment, and mechanism for shifting said pinion out of mesh with said gear comprising a rod 55 slidably mounted above said horizontal frame portions, connections between said rod and pinion and a lever for controlling the movements of said rod located upon the same side of said attachment as said brake operating mechanism, all of said operating parts 60 being located within the space defined by the bearing-carrying frame members.

In testimony whereof I affix my signature.
HARRY S. MYERS.
